CLAIM

The ornamental design for a light fixture, as shown and described.

DESCRIPTION

FIG. 1 is a perspective view of a light fixture in accordance with the design;

FIG. 2 is a front view thereof;

FIG. 3 is a top plan view thereof;

FIG. 4 is a right side view thereof; and,

FIG. 5 is a left side view thereof.

Any broken lines present in the drawings are for illustrative purposes only and form no part of the design to be patented.
